[57] **CLAIM**

The ornamental design for a perfume bottom, as shown and described.

DESCRIPTION

FIG. 1 is a front elevational view of a perfume bottle showing my new design;

FIG. 2 is a rear elevational view thereof;

FIG. 3 is a bottom plan view thereof;

FIG. 4 is a top plan view thereof;

FIG. 5 is a side elevational view thereof with the closure shown in an alternate open position, the side opposite that shown in FIG. 5 being the mirror image thereof;

FIG. 6 is a side elevational view thereof, the side opposite that shown in FIG. 6 being the mirror image thereof; and, FIG. 7 is a front elevational view thereof, but with the closure shown in an alternate open position and showing the bottom view of the closure.
